UNITED STATES PATENT OFFICE.

ARTHUR C. MILLER, OF NEWTON, MASSACHUSETTS.

HONEYCOMB-STRIPPER.

SPECIFICATION forming part of Letters Patent No. 731,701, dated June 23, 1903.

Application filed December 15, 1900. Serial No. 39,952. (No model.)

To all whom it may concern:

Be it known that I, ARTHUR C. MILLER, a citizen of the United States, residing at Newton, in the county of Middlesex and State of Massachusetts, have invented a new and useful Improvement in Honeycomb-Strippers, of which the following is a specification.

In the commercial production of honey section-frames are used. These are usually of rectangular form. The wax cells are united at the center of the frame or section and extend in opposite directions to the opposite sides, forming two planes of cells. The outer covering of the two sets of cells requires to be removed to extract the honey from the comb. This has heretofore been done by means of the "uncapping-knife." The outer surfaces of a honeycomb are not a true plane, but form an irregular surface. The uncapping-knife when used to uncap the cells cannot follow the irregularities of the surface and causes loss of honey, even in experienced hands, by cutting through some of the cells to secure the uncapping of all the cells in the comb.

The object of this invention is to avoid the loss of honey and facilitate the uncapping of the cells.

To this end the invention consists in the peculiar and novel construction and combination of a series of yielding cutters whereby the uncappers follow the irregularities of the surface, as will be more fully set forth hereinafter.

Figure 1 is an end view of my honeycomb-stripper, showing the uncapping-knives in the normal position in solid lines and in the operative position in broken lines. Fig. 2 is a side view of the same. Fig. 3 is a top view. Fig. 4 is an enlarged detail showing the pivotal connection of the uncapping-knives with the slide and the spring on the same. Fig. 5 is a side view, partly in section, of the cutting end of one of the uncapping-knives.

Similar letters of reference indicate corresponding parts in all the figures.

In the drawings, A indicates the base, from which the sides A' A' project. The base A is in the preferred form adapted to be secured to any suitable vertical surface by means of the screws A² A², so that the front is open for

the more convenient guiding of the section-frame containing the comb. The slides b are provided with the slots b' b' and are held to the sides A' A' by the screws b² b² to slide on the sides. The ends of the slides b b are provided with pins extending into slots in the ends of the arms b³ b³, which are secured one to each end of the two rock-shafts b⁴ b⁴, supported in bearings in the two sides A' A'. The rock-shafts b⁴ b⁴ are also provided at the base ends with the arms b⁵ b⁵, having pins on their outer ends which engage with the grooves in the slide b⁶.

In the drawings the slide b⁶ is shown drawn out and the uncapping-knives advanced toward the center. In Fig. 1 the connections of the slide b⁶ with the arms connecting with the rock-shafts b⁴ are indicated in broken lines.

The uncapping-knives c are pivotally supported on the rods c', which extend along the inner sides of the slides b b. The springs c² c² engage at one end with the groove c³ on the under sides of the slides b b, are coiled around the rods c', and bear on the upper side of the knives, holding the same in their normal position against the raised stops c⁴ on the slides. The uncapping-knives c are formed, preferably, of sheet-steel bent to form the feeler-surface c⁵ above the hook-shaped cutter edge c⁶. By this construction the feeler-surface of the knives bears on the wax surface of the comb and controls the position of the cutting edges of the knives to follow the irregularity of the outer surface of the honeycomb and cut off the wax closing the cells.

When my improved honeycomb-stripper is in use, the comb is passed downward between the uncapping-knives, which are pressed by the springs c² c², with the feeler-surfaces c⁵ bearing on the wax surface and the cutting edges behind the wax film closing the cells.

In entering and withdrawing the frame or section in which the comb is supported the slide b⁶ may be pushed in, and thereby the rock-shafts and the arms secured to the same operated to move the slides b and the uncapping-knives farther apart.

In practice I find that by having the hook-shaped cutting edges c⁶ of the knives c oblique to the plane of the knives I secure a

cleaner drawing cut on the wax and a cleaner uncapping than the straight-edge knives heretofore used.

Having thus described my invention, I claim as new and desire to secure by Letters Patent—

1. The combination of a row of pivoted spring-actuated knives each independent of the other, and having its cutting edge at an angle to the plane in which the knife moves on its pivot, substantially as and for the purpose set forth.

2. The combination of a row of pivoted spring-actuated knives each independent of the other, and having its cutting edge at an angle to the plane in which the knife moves on its pivot, the knives being so arranged that the shanks thereof engage the surface of the material that is to be cut or stripped, and serve as a feeler for properly positioning the knife, substantially as and for the purpose set forth.

3. The combination of two rows of pivoted spring-actuated knives each acting independently and having its cutting edge at an angle to the plane in which the knife moves on its pivot, the knives of each row having their cutting edges projecting in toward each other so that the material entered between the two rows may be cut or stripped upon opposite sides, the knives being so arranged that their shanks act as feelers upon the surface of the material that is to be cut so that each knife may be positioned in accordance with the formation of the surface which passes over the shank thereof, substantially as and for the purpose set forth.

4. The combination of a row of pivoted spring-actuated knives *c*, acting independently of each other and having the cutting edge *c*⁶ arranged at an angle to the plane in which the knife moves on its pivot, the shank of each knife being bent to form a feeler-surface *c*⁵, substantially as and for the purpose set forth.

5. The combination of two rows of pivoted spring-actuated knives each acting independently and having its cutting edge at an angle to the plane in which the knife moves on its

pivot, the knives of each row having their cutting edges projecting in toward each other so that the material entered between the two rows may be cut or stripped upon opposite sides, the knives being so arranged that their shanks act as feelers upon the surface of the material that is to be cut so that each knife may be positioned in accordance with the formation of the surface which passes over the shank thereof, the said rows of knives being relatively adjustable toward and away from each other, and means for effecting such adjustment, substantially as and for the purpose set forth.

6. In a honeycomb-stripper, two rows of uncapping-knives having feeler-surfaces and curved oblique cutting edges, the said rows of knives supported on opposite sides of the device, and springs acting on the knives, whereby when a comb is drawn through the stripper the feelers control the positions of the knives, as described.

7. In a device of the nature described, the combination with two side supports, of slides having capacity to be moved toward and from each other, of the knives *c* *c* pivotally supported on the slides, springs bearing on the knives, and means for operating the slides whereby the knives may act on the opposite sides of a honeycomb drawn through the device to uncap the cells, as described.

8. In a device of the nature described, the combination with the two side supports *A* *A*' and the slides *b*, of a series of uncapping-knives, pivotal supports for the knives on the slides, springs bearing on the knives, a feeler-surface on the knives, and oblique hook-shaped cutting edges on the knives, whereby each knife is held against and follows the surface of the comb to guide the cutter, as described.

In testimony whereof I have signed my name to this specification in the presence of two subscribing witnesses.

ARTHUR C. MILLER.
